DRAFT GEAR

Robert B. Cottrell and Frederick C. Kulieke, Chicago, Ill., assignors to American Steel Foundries, Chicago, Ill., a corporation of New Jersey

Application February 7, 1938, Serial No. 189,037

25 Claims. (Cl. 213—32)

Our invention relates to railway draft gears of the class generally designated barrel type in which the operating parts are enclosed within a casing or housing.

5 A general object of our invention is to devise an improved form of draft gear wherein a plurality of sets of shoes are arranged to operate in series. The generic form of such a type of gear has been more particularly described in the co-
10 pending application in the name of R. B. Cottrell, Serial No. 172,925, filed in the United States Patent Office November 5, 1937.

Another object of our invention is to device a draft gear of the series wherein the forces of impact and release are transmitted directly from one set of shoes to another without intervening means such as a wedge block.

Our invention further contemplates a type of draft gear structure wherein the manner of co-
20 operation between the friction producing parts is such as to reduce to a minimum frictional forces tending to prevent close alignment between the frictional surfaces on the housing and the abutting frictional surfaces of the shoes, thus
25 permitting these surfaces to be in full and even contact throughout the stroke of impact and the movement of release.

Our invention also comprehends a type of gear wherein the number of shoes of each set is such
30 as to admit of relatively greater manufacturing tolerances than is the case in a gear in which wedging means contacts a greater number of shoes as, for example, three or more.

A specific object of our invention is a design
35 of series cross-equalized type of gear comprising a plurality of sets of shoes wherein the shoes of one set intervene between the shoes of the other set and wherein the shoes of the respective sets have engagement with each other along dia-
40 gonally arranged surfaces.

A still further object of our invention is to de-
sign a series cross-equalized type of gear com-
prising a plurality of sets of two shoes each
45 wherein each shoe of each set has direct en-
gagement with both shoes of the other set.

A further object of our invention is to devise
a gear as above described wherein one set of
shoes will have abutment against the compres-
50 sion spring of the gear, the other set of shoes
will have abutment against the follower wedge
and each shoe of each set will have abutment
with a plurality of shoes of another set.

A still further object of our invention is to de-
55 vice a series cross-equalized type of gear in which
the forces of impact and reaction are transmitted

directly through the successive sets of shoes without intervening means.

Our invention also comprehends a type of gear wherein the space required for the friction developing shoes is reduced to a minimum by 5 arranging the shoes for direct engagement with each other.

Our invention has the further object of de-
signing a gear wherein not more than two shoes
have abutment against a single wedging means
thereby equalizing the shoe pressures and elim-
inating the necessity for any such special ar-
rangements as crowning one or the other of two
abutting surfaces in order to secure engagement
10 between a single wedging means and a larger
number of shoes as, for example, three or more.
In other words, a natural equalizing arrange-
ment occurs more or less independently of the
character of the engaging surfaces when a
15 wedging member is interposed between two
shoes.

Our invention has for a further object a de-
sign of draft gear in a housing of oval shape
in which substantially the entire internal sur-
face at one end thereof will be availed of as a 25
frictional area whereby maximum benefit may
be obtained from the draft gear space allotted in
the standard A. A. R. car construction. It is
well known, of course, that this standard draft
gear pocket is of a rectangular shape having 30
greater width than depth. An oval shaped
housing is therefore best accommodated by the
standard pocket because it makes maximum use
of space available while, at the same time, ap-
proximating the cylindrical shape which offers 35
greatest resistance to bursting pressure.

In the drawings Figure 1 is a plan view of one
form of a draft gear embodying my invention,
one-half of the view being in section, the sec-
tion being taken substantially in the plane indi- 40
cated by the line 1—1 of Figure 3;

Figure 2 is a side elevation of the gear struc-
ture shown in Figure 1, half in section, the sec-
tion being taken in the plane substantially as
indicated by the line 2—2 of Figure 3;

Figure 3 is an end view the view being taken
from the left as seen in Figures 1 and 2 and from
the outer or open end of the gear, with the fol-
lower wedge removed and other parts seated in
50 their normal positions.

Figure 4 is a fragmentary sectional view
through two shoes, one of each set, and shows
the manner of cooperation therebetween, the
section being taken longitudinally of the gear and 55

substantially in the plane indicated by the line 4—4 of Figure 3;

Figure 5 is a top plan view of the follower wedge;

5 Figure 6 is a side elevation thereof, half in section, the section being taken substantially in the plane bisecting the wedge on the long diameter thereof and as indicated by the line 6—6 of Figure 5;

10 Figure 7 is an end elevation of the follower wedge, half in section, the section being taken substantially in the plane bisecting the wedge on the short diameter thereof and as indicated by the line 7—7 of Figure 5;

15 Figure 8 is an elevational view of the inner face of one shoe of the outer set;

Figure 9 is an end elevation thereof, the view being taken from the inner end and Figure 10 is a sectional view substantially in the plane bi-

20 secting the shoe longitudinally and as indicated by the line 10—10 of Figure 8;

Figure 11 is an elevational view of the inner face of one shoe of the inner set;

25 Figure 12 is an end elevation thereof, the view being taken from the inner end of the shoe and Figure 13 is a sectional view substantially in the plane bisecting the structure longitudinally and as indicated by the line 13—13 of Figure 11;

30 Figure 14 is a fragmentary view of a modified form of our improved draft gear, the view being half in section and corresponding generally to that shown in Figure 1;

35 Figure 15 is a sectional view of the release spring follower used in the modification of our improved form of gear shown in Figure 14, the section being taken substantially in the plane indicated by the line 15—15 of Figure 16;

40 Figure 16 is an end elevation of said release spring follower, the view being taken from the outer end thereof; and

45 Figures 17 and 18 are transverse sectional views through the housing structure, the section shown in Figure 17 being taken nearer the closed end of the housing and substantially in the plane indicated by the line 17—17 of Figure 2, and the section of Figure 18 being taken nearer the open end of the housing and substantially in the plane indicated by the line 18—18 of Figure 2.

50 Describing our novel gear structure in more detail, it comprises the barrel or housing 2 similar in form to that shown in the co-pending application Serial No. 182,559, filed in the United States Patent Office December 30, 1937, in the name of R. B. Cottrell, said housing having the 55 base flange 4, walls of generally rectangular form adjacent said base as most clearly seen in Figure 17, said rectangular shape extending from said base for approximately one-third the length of said housing and merging at the middle portion 60 of said housing into the generally oval-shaped walls, best shown in Figure 18, said oval shape extending from the central portion of said housing to the open end thereof. Centrally formed in the base of the housing is the cavity 6 which 65 forms a convenient receptacle for the head 8 of the retaining bolt 10, the walls of said cavity forming an inwardly projecting stud indicated at 12, said stud providing suitable positioning means for the outer large coil spring 14 and presenting 70 on its inner face suitable seating means for the small inner coil spring 16. Adjacent the base of the housing and in the opposite walls thereof are formed the openings 18 beaded around their edges as at 20, 20 and suitable for drainage purposes when the assembled gear is stood on end as 75

well as facilitating the removal of cores used in the process of casting housings. Adjacent the open end of the housing and at opposite sides thereof are formed the relatively wide V-shaped tapering friction faces 22, 22 against which are seated the outer shoes 24, 24 and, likewise, at the intervening sides of the open end of the housing are formed the relatively narrow V-shaped friction surfaces 26, 26 against which may be seated the inner shoes 28, 28. The general configuration 10 of the open end of the housing is best seen from a consideration of Figure 3 wherein also may be observed the overlapping relationship of the inner and outer shoes as well as the manner in which the respective sets of shoes are seated 15 against the V-shaped friction surfaces of the housing. The outer friction shoes 24, 24 present the diagonal faces 30, 30 (Figure 2) against which may be seated the diagonal surfaces 32, 32 presented on the opposite sides of the inner face 20 of the follower wedge 34. The outer shoes 24, 24 abut the inner set of shoes along diagonal faces as indicated at 36 (Figure 1) and the inner shoes are seated against the outer ends of the coil springs 14 and 16 as best seen at 38 (Figures 1 25 and 2). The follower wedge 34 presents on its outer face the cup-like cavity 40 which forms a convenient receptacle for the securing nut 42 of the retaining bolt 10.

30 The detailed structure of the follower wedge is shown in Figures 5 to 7, inclusive, wherein it may be observed that it consists of a generally oval-shaped cup-like structure presenting on its inner face the before mentioned diagonal surfaces 32, 32 for engagement with the outer set of friction shoes and having on its outer face the oval cavity 40 forming a convenient receptacle for the nut of the retaining bolt 10 as before mentioned. Centrally formed in the base or inner wall of the follower wedge is the bolt opening 44, the smooth 40 outer edges of the annular walls of the follower wedge presenting plane surfaces as indicated at 46 for abutment of the usual follower block.

45 The detail of the outer friction shoe is shown in Figures 8 to 10, inclusive, wherein it may be observed that the structure comprises a generally V-shaped outer wall 47 presenting the smooth outer surfaces 48, 48 for abutment against the V-shaped friction surfaces 22 of the housing and having the relatively heavy body portion 49 with the outer diagonal face 30 for abutment of the diagonal face 32 of the follower wedge. Centrally formed in the body portion 49 is the lightening cavity 50. The central portion of the base as indicated at 52 lies in a plane substantially at right angles to the axis of the gear, and on opposite sides of said base are formed the diagonally arranged plane surfaces 54, 54 providing abutment for the cooperating surfaces 56 on the inner shoes. Centrally formed on the body portion 49 is a cylindrical groove 58 (Figure 9) providing clearance for the securing bolt 10 when the parts are in assembled relationship.

55 The detail of the inner friction shoe is shown in Figures 11 to 13. It will be observed that the shoe is a compact forging having the generally V-shaped outer wall 60 presenting the frictional surfaces 62, 62 for abutment against the before mentioned surfaces 26 of the housing (Figure 1). The shoe also has the relatively heavy central body portion 64 with the diagonally arranged outer surfaces 56, 56 lying in a single plane and separated by the shallow central groove 66, said surfaces 56 having engagement with the surfaces 54 of the respective outer shoes. The inner face 70 75

of the central body portion 64 presents a surface 68 lying in a plane substantially normal to the axis of the gear.

From a consideration of Figures 9, 10, 12 and 5 13 it may be observed that the surfaces 48, 48 of the outer shoes and 62, 62 of the inner shoes have a slight taper with respect to the axis of the gear, thus accommodating themselves more readily to the form of the internal surface of the housing at 10 the frictional end thereof.

Figure 14 shows a gear generally similar to that shown in Figures 1 to 3 with the housing 2, the inner friction shoes 28, 28 and the outer friction shoes 24, 24, the follower wedge 34 and 15 the retaining bolt 10, all substantially identical to the corresponding parts of the gear shown in Figures 1 to 3. In this modification, however, I have provided the large outer compression spring 114, the intermediate compression spring 116 and 20 a release spring 118. The large and intermediate compression springs 114 and 116 have abutment against the inner shoes 28, 28 as at 38. The release spring 118 has abutment as at 120 against the inner flanged end of the release spring follower 122, the opposite end of which has abutment as at 124 against the follower wedge 34, thus facilitating the opening of the gear after a 25 compression stroke. The form of the release spring follower 122 is shown in Figures 15 and 16 wherein it may be observed that it comprises a thimble flanged at the inner end as at 126 for abutment of the release spring 118 and presenting a smooth annular surface at the opposite end as at 128 for abutment of the follower wedge 34, 30 the central opening 130 permitting said follower to be sleeved upon the securing bolt 10 as a convenient retaining means therefor.

From the foregoing it will be apparent that the diagonal faces 32, 32 on opposite sides of the 40 follower wedge engage diagonal faces 30, 30 on the outer shoes in two planes, said planes intersecting in a line traversing the long diameter of the housing and, therefore, at right angles to the axis of the gear; also that the diagonally arranged surfaces 56, 56 of the inner friction shoes 45 engage the friction surfaces 54, 54 on the outer friction shoes in two planes which intersect in a line traversing the short diameter of the housing and, likewise, perpendicular to the axis of the 50 gear.

It is to be understood that we do not wish to be limited by the exact embodiment of the device shown which is merely by way of illustration and not limitation as various and other forms of the 55 device will of course be apparent to those skilled in the art without departing from the spirit of the invention or the scope of the claims.

We claim:

1. In a friction absorbing device a housing 60 having inner friction surfaces adjacent the open end, resilient means, a wedge follower, and outer and inner sets of shoes in alternate arrangement against said surfaces, each shoe of each set having abutment with a plurality of 65 shoes of another set whereby the forces of impact and release are transmitted from said follower directly through said shoes to said resilient means.

2. In a friction absorbing device a housing 70 having an oval-shaped friction end with internal friction faces, resilient means, a follower wedge, and a plurality of sets of shoes in alternate arrangement within said oval end, one set of said shoes having abutment against said wedge, another set of said shoes abutting said means, the

sets of said shoes abutting each other on faces lying in two planes which projected intersect on the short diameter of said oval end.

3. In a friction device a housing having an oval friction end with V-shaped internal friction surfaces, resilient means, a follower wedge, and sets of shoes in alternate arrangement against said surfaces, said sets of shoes being arranged in series between said wedge and said means with the shoes of one set abutting said wedge, the 10 shoes of the other set abutting said means, and the sets abutting each other on faces lying in two planes which projected intersect on the short diameter of said oval end.

4. In a friction device a housing having an oval friction end with internal friction surfaces, resilient means, a follower wedge, and a plurality of sets of shoes in alternate arrangement against said housing between said wedge and said means, one set abutting said wedge in diagonal planes 20 and abutting said other set in other diagonal planes, said first mentioned diagonal planes when projected intersecting in a line at right angles to the line defining the intersection of the projection of said other diagonal planes.

5. In a friction absorbing device a housing having an oval-shaped friction end with a plurality of V-shaped internal friction surfaces, a plurality of sets of friction shoes seated in alternate arrangement against said surfaces, resilient 30 means and a wedge follower in abutment with said sets respectively, each shoe of each set having engagement with two shoes of another set whereby the forces of impact and release are 35 equalized among said several shoes.

6. In a friction absorbing device affording direct engagement between respective sets of shoes by interposing each shoe of each set between a plurality of shoes of another set, a housing having an oval open end with two pairs of opposed 40 internal friction surfaces extending substantially therearound and aligned along the long and short axes of said oval end, said axes being substantially at right angles to each other, resilient means, a follower wedge, and two sets of shoes 45 arranged in series between said wedge and said resilient means and against said pairs of friction surfaces respectively with each shoe of each set having abutment against both shoes of the other set, said shoes occupying substantially the entire frictional area around the friction end of said housing, the shoes of one set abutting said wedge on diagonally outwardly directed faces and abutting the shoes of the other set on diagonally inwardly directed faces, whereby the 55 forces of impact and release are transmitted directly from said wedge through said shoes to said means.

7. In a friction absorbing device affording direct thrust from one set of shoes to another 60 thereof, an oval housing having two sets of internal tapering friction surfaces extending substantially around the open end thereof, two sets of shoes arranged in series and alternately seated against said surfaces on axes substantially at 65 right angles to each other and occupying substantially all of said friction surfaces, a wedge follower, and resilient means, one set of said shoes having abutment against said follower wedge and the other set of said shoes abutting said resilient means, both shoes of each set having abutment with both shoes of the other set along planes diagonal with respect to the axis of said gear, whereby forces of impact are transmitted through one set of shoes directly to the 70 75

- other set of shoes and both sets of shoes react against said housing.
8. In a friction absorbing device affording thrust engagement between two sets of shoes by 5 a direct engagement of each shoe of each set with a plurality of shoes of another set, a housing having an oval open end with two pairs of internal friction surfaces extending substantially therearound, one set of said surfaces being on the 10 long axis and the other set on the short axis thereof, two sets of diametrically opposed friction shoes alternately arranged against said surfaces and utilizing substantially all of the frictional area of said oval end, the shoes of respective 15 sets being in overlapping relationship longitudinally of said gear, a wedge follower, and resilient means, one set of said shoes having abutment with said wedge follower, the other set of said shoes abutting said resilient means, the engaging 20 surfaces between the shoes of respective sets being along diagonal planes, whereby the forces of impact and release are transmitted directly from said wedge through said shoes to said means.
- 25 9. In a friction absorbing device, a housing having internal tapering friction surfaces substantially surrounding the open end thereof, said surfaces being arranged in opposed pairs along axes substantially at right angles to each other, 30 sets of shoes arranged in series and alternately seated against said surfaces with the shoes of the respective sets arranged against said housing in overlapping relationship longitudinally of said housing, one set of said shoes abutting said follower and the other set abutting said means, each shoe of each set having abutment with both shoes of the other set.
- 35 10. In a friction absorbing device, a housing having substantially continuous internal tapering friction surfaces around the oval open end thereof, said surfaces being arranged in two sets along axes substantially at right angles to each other, resilient means, a wedge follower, and two sets of shoes arranged in series between said 40 means and follower with the shoes of respective sets alternately seated against said friction surfaces in overlapping relationship longitudinally of said housing and utilizing substantially all of the frictional area thereof, the shoes of one set abutting said resilient means and the shoes of the other set abutting said follower, each shoe of each set having wedge abutment between the shoes of the other set.
- 45 11. In a draft gear a housing having internal friction surfaces, resilient means, a wedge follower, and outer and inner sets of friction shoes arranged in tandem and seated in alternate formation against said surfaces, each shoe of each set having abutment against two shoes of another set, one set of said shoes having abutment with said follower wedge and another set of said shoes having abutment with said resilient means.
- 50 12. In a friction device a barrel housing having an internal oval friction end, resilient means, a follower wedge, and a plurality of sets of shoes in alternate arrangement within said oval end, one set abutting said wedge, another set abutting said means, and each shoe of each set abutting a plurality of shoes of another set along surfaces 55 lying in planes which project intersect on the short diameter of said oval end.
- 55 13. In a friction device a housing having an interval oval friction end with V-shaped friction surfaces, resilient means, a follower wedge, and sets of shoes in alternate arrangement against 60
- said surfaces, said sets of shoes being arranged in series between said wedge and said means with each shoe of each set in abutment with two shoes of another set.
- 65 14. In a friction absorbing device a housing having internal friction surfaces adjacent the open end, resilient means, a wedge follower, and outer and inner sets of shoes in alternate arrangement against said surfaces between said means and said follower, each shoe of each set having abutment against a plurality of shoes of a different set whereby the pressures of impact and release are equalized among said several shoes.
- 70 15. In a friction device a barrel housing having an internal oval friction end, resilient means, a follower wedge, and a plurality of sets of shoes in alternate arrangement within said oval end, one set abutting said wedge, another set abutting said means, and each shoe of each set abutting a plurality of shoes of another set.
- 75 16. In a friction absorbing device a housing having internal friction surfaces adjacent the open end, resilient means, a wedge follower, and outer and inner sets of shoes in alternate arrangement against said surfaces between said means and said follower, each of said shoes having abutment with a plurality of shoes in a different set.
- 80 17. In a friction absorbing device, a housing having inner friction surfaces adjacent the oval open end thereof, resilient means, a wedge follower, and a plurality of sets of shoes in alternate arrangement against said surfaces, each shoe of each set having abutment with a plurality of shoes of another set whereby the forces of impact and release are transmitted from said follower directly through said shoes to said resilient means, said abutting surfaces at opposite sides of the device defining planes which intersect on the short axis of said oval end.
- 85 18. In a friction absorbing device, a housing having inner friction surfaces adjacent the open oval end, resilient means, a wedge follower, and a plurality of sets of shoes in alternate arrangement against said surfaces having an overlapping relationship longitudinally of said housing, each shoe of each set having abutment with a plurality of shoes of another set whereby the forces of impact and release are transmitted from said follower directly through said shoes to said resilient means, said abutments at opposite sides of said device defining planes which intersect on the short axis of said oval end.
- 90 19. In a friction absorbing device, a housing having an oval-shaped friction end with a plurality of V-shaped internal friction surfaces, a plurality of sets of friction shoes seated in alternate arrangement against said surfaces, resilient means, and a wedge follower, each shoe of each set engaging two shoes of another set whereby the forces of impact and release are equalized among said several shoes, said engaging surfaces lying in planes projections of which intersect on the short axis of said oval end.
- 95 20. In a draft gear, a housing having an oval open end with internal friction surfaces, resilient means, a wedge follower, and outer and inner sets of friction shoes arranged in tandem and seated in alternate formation against said surfaces, each shoe of each set having abutment against two shoes of another set, one set of said shoes having abutment with said follower wedge and another set of said shoes having abutment with said resilient means, the abutting surfaces between the shoes of said respective sets defining

two planes which projected intersect on the short axis of said oval end.

21. In a draft gear, a housing having an oval open end with internal friction surfaces, resilient means, a wedge follower, and outer and inner sets of friction shoes arranged in tandem and seated in alternate formation against said surfaces, each shoe of each set having abutment against two shoes of another set, one set of said shoes having abutment with said follower wedge and another set of said shoes having abutment with said resilient means, the engaging surfaces between said follower wedge and the abutting shoes lying in two planes which projected intersect on the long axis of said oval end.

22. In a friction absorbing device, a barrel housing having a generally oval open end with sets of opposed tapering friction surfaces arranged substantially therearound, the surfaces of each set being arranged along one axis of said oval end, and clutch mechanism comprising resilient means, a wedge follower, and two sets of opposed shoes in abutment with said sets of friction surfaces respectively, each shoe of each set having abutment with both shoes of the other set, whereby forces of impact and release are transmitted directly through said shoes between said means and follower.

23. In a friction absorbing device of the barrel type, a housing having an oval open end with pairs of opposed tapering internal friction surfaces extending substantially therearound, each

set of surfaces being arranged along one axis of said oval end, and clutch mechanism comprising a wedge, resilient means and sets of shoes interposed between said wedge and means and seated respectively against said sets of surfaces, each shoe of each set having abutment with both shoes of the other set.

24. In a friction absorbing device of the barrel type, a housing having an oval open end with pairs of opposed tapering internal friction surfaces extending substantially therearound, each set of surfaces being arranged along one axis of said oval end, and clutch mechanism comprising a wedge, resilient means and sets of shoes interposed between said wedge and means and seated respectively against said sets of surfaces, both shoes of each set abutting both shoes of the other set.

25. In a friction absorbing device of the barrel type, a housing having an oval open end with pairs of opposed tapering internal friction surfaces extending substantially therearound, each set of surfaces being arranged along one axis of said oval end, and clutch mechanism comprising a wedge, resilient means and sets of shoes interposed between said wedge and means and seated respectively against said sets of surfaces, each shoe having abutment with two shoes of the other set.

ROBERT B. COTTRELL.

FREDERICK C. KULIEKE.
